UNITED STATES PATENT OFFICE.

WILLIAM DEMUTH, OF NEW YORK, N. Y.

DESIGN FOR PIPE-STEMS.

Specification forming part of Design No. **11,362**, dated August 26, 1879; application filed June 12, 1879
[Term of patent 7 years.]

To all whom it may concern:

Be it known that I, WILLIAM DEMUTH, of the city, county, and State of New York, have originated and designed a Pattern for Pipe-Stems, of which the following is a full, clear, and exact description, reference being had to the accompanying drawings, making part of this specification.

This design is represented in the accompanying drawings, in which—

Figure 1 represents a stem in perspective view containing my design. Figs. 2, 3, and 4 are detail views of the prism.

Similar letters indicate corresponding parts. My design is applied to stems of tobacco-pipes; and consists of a mouth-piece provided with an ordinary molding and terminating at its lower end in a molding, the base of which rests upon a prism or parallelopipedon, the exposed faces of which are ornamented with figures, and below such ornamental body is a peculiar shaped molding, the end of the stem terminating in the usual molding and reduced portion to receive a cork as ordinarily.

In the drawings, the letter A designates a pipe-stem, the mouth-piece of which is provided with the usual molding C, and terminates at its lower end in a molding, a, the base of which rests upon a block having the shape of a prism or parallelopipedon, the exposed faces of which are ornamented, as shown in the accompanying illustration.

Below the ornamented prism or parallelopipedon is a peculiar shaped molding, b, and below the same is the usual or ordinary molding D, and the stem at its end is provided with a reduced portion to receive the cork or to enter the opening in the pipe.

It will be seen from the foregoing, taken in connection with the accompanying illustration, that I have produced a stem having a novel and distinguishing appearance, and the same is chiefly secured by interposing between the two peculiar shaped moldings a b the prism or parallelopipedon block having its exposed faces ornamented.

What I claim is—

The design for a pipe-stem, as herein shown and described, the same consisting of a mouth-piece having at its lower end the molding a, the base of which rests upon a prism or parallelopipedon, the exposed faces of which are ornamented, and below which ornamented prism or parallelopipedon is the ornamental molding b, as set forth.

In testimony that I claim the foregoing I have hereunto set my hand and seal.

WM. DEMUTH. [L. S.]
